UNITED STATES PATENT OFFICE.

WILLIE L. NORTHAM, OF ARLINGTON, INDIANA.

GATE.

SPECIFICATION forming part of Letters Patent No. 781,964, dated February 7, 1905.

Application filed October 22, 1904. Serial No. 229,524.

To all whom it may concern.

Be it known that I, WILLIE L. NORTHAM, a citizen of the United States, residing at Arlington, in the county of Rush and State of Indiana, have invented new and useful Improvements in Gates; and I do declare the following to be a full, clear, and exact description of the invention, reference being had to the accompanying drawings, and to the letters and figures of reference marked thereon, which form a part of this specification.

This invention relates to swinging gates, particularly to the larger sizes that are adapted to be elevated more or less for avoiding snow-drifts, for grading live stock, or for other purposes, the invention having particular reference to various features of construction relating to the framing of the gate proper, to the hanging and elevating devices, and to the latching appliances thereof.

Particular objects of the invention are to provide strong and light-weight gates, improved hanging apparatus for the gates, and improved means for elevating and holding the gates in adjusted positions; and a further object is to provide inexpensive, durable, and economical gates having such improvements which may be easily operated.

With the above and other objects in view the invention consists in a gate provided with an improved roller-bearing normally supporting the weight of the gate, a hinge-rod, and rollers or wheels engaging the hinge-rod and together holding the gate in substantially level position, the gate being also provided with a pulley or wheel, a cable, and a lever or similar device for adjusting the gate to various positions above the normal position thereof.

The invention consists, further, in the novel parts and in the novel combinations and arrangements of parts, as hereinafter particularly described and claimed.

Referring to the drawings, Figure 1 is a side elevation of a gate including the hinge-post and the latch-post therefor having the improvements embodied in the construction thereof; Fig. 2, an elevation of the free end of the gate; Fig. 3, a fragmentary side eleva-

tion showing the gate fully elevated; Fig. 4, 50 an elevation of the hinge-post; Fig. 5, an elevation of the hinge-rod; Fig. 6, an elevation of the hinge end of the gate; Fig. 7, a fragmentary elevation of the latch-post; Fig. 8, a top plan of the gate complete, a portion of 55 the top rail being broken away; Fig. 9, a fragmentary horizontal section taken a short distance above the bottom rail of the gate; Fig. 10, a fragmentary horizontal section on the line 1 1 in Fig. 1; Fig. 11, a fragmentary 60 horizontal section on the line 2 2 in Fig. 1; Fig. 12, a perspective view of the roller-bearing for the gate and its support detached from the hinge-post; Fig. 13, a fragmentary side elevation showing the gate partially elevated; 65 Fig. 14, a perspective view of one of the gate-latches; Fig. 15, a horizontal section of the latch-post at the plane of the latches; Fig. 16, a fragmentary elevation of the latch-post and latches, and Fig. 17 a perspective view 70 of the base-plate that supports the latches.

Similar reference characters in the several figures of the drawings designate corresponding parts or features.

In construction any suitable materials may 75 be employed, the hinge-post *a* and the latch-post *b* being suitably set in the ground. The post *a* is provided with a suitable support *A*, on which is mounted a roller *B* and which is placed somewhat above the ground-surface, so 80 as not to be affected by sand or dust, snow or ice. Above the roller two hinge members *c* and *d* are attached to the post, and a similar hinge member *e* is attached also to the post below the roller and near the ground. A 85 headed hinge-rod *f* extends through the hinge members *c* *d* *e* and may be removed therefrom when necessary. A cotter *g* is inserted in a suitable hole in the lower end of the rod *f* beneath the member *e* to prevent accidental 90 upward movements of the rod. A collar *C* is adjustably secured to the rod *f* by means of a set-screw *h*, the collar being below the roller-support *A*. The support *A* comprises an axle *i* that extends through the post *a*, a nut *j* being 95 applied to the end of the axle against the rear side of the post. On the axle is a collar *k*, providing a shoulder against the front of the

post, the roller B operating freely between the collar and a suitable shoulder of the axle. In the support A is a hole *l*, in which is secured a hook-bolt *m*, that binds the rod *f* 5 against the support and prevents rotation of the rod and also affords a lateral support therefor.

The latch-post is provided with a pair of latches D and D' of identical form in order 10 to permit the gate to operate in two directions. The latches are both mounted on a single base-plate E, which has ears *n* and *n'* in pairs at its rear side, there being a slot *o* in the plate extending between both pairs of 15 ears. Each latch has an arm *p*, that is pivoted to a pair of the ears, and the latch also has a projection *q*, that guides a spring *r*, which is seated in the post and presses against the latch, the latter having an operating-handle 20 that bears against the base-plate, resisting the spring.

The gate proper comprises a frame including a main bar F, supporting a bottom rail G and a top rail H, to which are attached an end 25 bar I, a truss-post J being attached to the top and bottom rails, and diagonal braces 3 4 5 6 7 8 9 10 attached to the main and end bars and the top and bottom rails; also, horizontal wires 11 12 13 are employed in the usual manner. The end bar I is provided with a latch-bar K, although the end bar I itself may be 30 adapted to serve the purpose of the bar K. A semicircular bearing L is secured to the main bar F and extends about the rod *f*, so as 35 to bear upon the roller-bearing B, riding thereon and coöperating therewith to support the gate when the latter is in motion and also when at rest in its normal lower situation. A pair of plates *s* and *s'* are attached to the upper 40 part of the gate-frame and extend beyond the bar F and the rod *f*, and a roller M is journaled between the plates and has a groove 14 guiding the roller on the rod *f*, the latter being between the bar F and the roller. At 45 the lower part of the gate-frame a pair of angle-plates *t* and *t'* are secured thereto and extend downwardly beyond the end of the bar F, and a roller N is journaled between the plates and has a groove 15 guiding the roller 50 on the rod *f*, the latter being beyond the roller.

A pulley O, having a groove 16, is attached integrally to the roller N; but the pulley may be otherwise connected to the roller, so that 55 both must move together on a common axis. A cable or chain P is attached at one end thereof to the collar C and extends under the pulley O to the lever Q, to which it is connected by means of a pin *v*, and the cable is 60 guided to the groove 16 by a guide *u*, that is attached to the bar F. The lever Q has an end pivoted to a support R, that is attached to the rail G and is arranged at one side of

the gate, a similar lever Q' being secured to the pivoted end of the lever Q and arranged 65 at the opposite side of the gate. The lever Q' is rather a convenience, however, and not a necessity. A movable button S is mounted on the rail G and adapted to be turned so as to lock either one of the levers Q or Q'. A 70 hook T is connected loosely to a pin *w*, that is attached to the rail G, and the free end of the hook is normally supported on a rest *x*, that is carried by the rail G, the hook having a laterally-bent finger *z*, adapted to engage 75 the lever Q to hold it in an intermediate position. The main bar F is provided with guards *y* *y'*, that are adapted to engage the rod *f* in case the rollers M and N should become disengaged from the rod; but the guards may in 80 some cases be dispensed with, they normally having no contact with the rod, but extending about it.

In practical use when the gate is closed it will be held by the latches D and D' and may be opened in either direction, in or out, after manipulating the proper latch to release it. When closing the gate, the latches operate automatically, as will be apparent, the springs *r* being compressed when the latches are 85 forced to rock on their pivots, so as to move out of the way of the bar K. Ordinarily the weight of the gate is carried by means of the bearings B and L and is held level and plumb by means of the rollers M and N engaging 90 the rod *f* and serving as hinging devices. When it is desired to elevate the gate to its maximum height, the lever Q should be moved radially from the position shown in Fig. 1 to the position shown in Fig. 3, resting on the 95 rail G, where it will be held automatically, but may be locked by the button S. The gate may be elevated to an intermediate position by connecting the hook T to the lever Q, as 100 in Fig. 13. When operating the lever Q, the cable lifts the roller N, and thereby causes the rollers M and N to roll along the rod *f*. When the gate is lowered and the lever Q returned to its normal position, as in Fig. 1, the lever is supported in an oblique position by 105 means of the lever Q', resting upon the rail G. The collar C may be adjusted in its position on the rod *f* to adjust the length of the cable P. This is a convenient arrangement; but it is obvious that the end of the cable may be 110 attached to the support A or to the post *u*, if desired, and if the bearings B and L are omitted the cable P will support the gate when lowered. It will be understood that the latches will operate at all times whether the 115 gate is elevated or not, the bar K being of proper length for the purpose. When either latch is operated to permit the gate to close, the opposite latch acts as a stop for the gate to prevent its passing the proper closed position. 120

Having thus described the invention, what I claim as new is—

1. A gate including a vertical hinge-rod, a post supporting the hinge-rod, a gate-frame, a roller supported by the frame in engagement with the hinge-rod and provided with an operating-wheel having the same axis therewith, an operating device connected with the wheel and controlling the rotative movements thereof, and a hinging device connected to the frame in engagement with the hinge-rod.

2. A gate including a post, a hinge-rod supported by the post, a gate-frame, an operating-wheel mounted on the gate, a roller secured to the wheel and engaging the hinge-rod, operating means mounted on the gate-frame and engaging the wheel, locking devices for the operating means, and a hinging device connected to the gate-frame in engagement with the hinge-rod.

3. A gate including a post, a hinge-rod supported by means of the post, a gate-frame provided with a pulley having a roller secured thereto in engagement with the hinge-rod, a cable or chain fixed at one end thereof to the gate-support and extending about the pulley, an operating device connected with the pulley, and a hinging device connected to the gate-frame in engagement with the hinge-rod.

30 4. A gate including a post, an axle secured to the post and having a roller mounted thereon, a hinge-rod supported by the post, a gate-frame provided with a semicircular bearing adapted to coöperate with the axle-roller, hinging devices carried by the gate-frame and coöperating with the hinge-rod, a pulley mounted on the gate-frame, a roller secured to the pulley in engagement with the hinge-rod, and a cable or chain coöperating with the pulley to disconnect and connect the bearing with the axle-roller.

5. A gate including a post, a hinge-rod mounted on the post, a gate-frame, a roller mounted on the upper part of the gate-frame and engaging the hinge-rod, a roller mounted on the lower part of the gate-frame and engaging the hinge-rod and having a pulley secured thereto, a cable or chain fixed at one end thereof to the gate-support and extending about the pulley, and a lever pivoted at one end thereof to the bottom of the gate-frame and connected to the cable or chain.

6. In a gate, a hinge-post having upper and lower hinge members, a support attached to the post intermediately of the hinge members, a bearing-roller mounted on the support, a hinge-rod extending through the hinge members and secured to the support, a gate-frame, hinging devices carried by the gate-frame and coöperating with the hinge-rod, and a semicircular bearing secured to the frame and operating with the bearing-roller.

7. In a gate, the combination with a hinge-

post and a hinge-rod mounted thereon, of a gate-frame, hinging devices connected to the gate-frame and movably engaging the hinge-rod, a pulley mounted on the gate-frame, a roller secured to the pulley and engaging the hinge-rod, a lever mounted on the gate-frame, a cable or chain engaging the pulley and connected at one end thereof to the lever, and an anchor device mounted on the gate-support and adjustably supporting the opposite end of the cable or chain.

8. In a gate, the combination with a hinge-post and a hinge-rod mounted thereon, of a gate-frame, hinging devices mounted on the gate-frame and movably engaging the hinge-rod, a pulley mounted on the gate-frame, a collar secured adjustably to the hinge-rod, a cable secured at one end thereof to the collar and engaging the pulley, and a lever pivoted at one end thereof to the gate-frame and connected to the other end of the cable.

9. In a gate, the combination with a hinge-post and a hinge-rod mounted thereon, of a gate-frame, a grooved roller mounted on the upper part of the frame and engaging the farther side of the hinge-rod, a grooved roller mounted on the lower part of the frame and engaging the nearer side of the hinge-rod and provided with an operating-pulley, a bearing-roller mounted on the hinge-post, a curved bearing attached to the gate-frame and adapted to coöperate with the bearing-roller, and a power device mounted on the gate-frame and coöperating with the pulley or wheel to raise or lower the gate-frame.

10. In a gate, the combination with a post and a hinge-rod mounted thereon, and with a gate-frame, of a support secured to the post and also to the hinge-rod, a bearing-roller mounted on the support, a semicircular bearing member secured to the gate-frame extending about the hinge-rod and engaging the bearing-roller, and guides carried by the gate-frame and coöperating with the hinge-rod.

11. In a gate, the combination with a post and a hinge-rod mounted thereon, and with a gate-frame, of a bracket secured to the gate-frame and projecting beyond the bottom thereof, a roller mounted in the bracket below the gate-frame and engaging the hinge-rod, a pulley connected to the roller, a hinge device attached to the top of the gate-frame in connection with the hinge-rod, a lever pivoted on the bottom of the gate-frame, a cable engaging the pulley and having one end thereof connected to the lever, and a support for the opposite end of the cable.

12. In a gate, the combination with a post and a hinge-rod mounted thereon, and with a gate-frame having a lower rail, of hinging devices connected to the gate-frame and engaging the hinge-rod, a pulley mounted on the gate-frame, a cable supported at one end there-

of by the gate-support and extending about the pulley, a lever pivoted at an end thereof on the lower rail of the gate-frame and normally extending upwardly obliquely toward the hinged end of the gate-frame and adapted to swing to the lower rail, means connecting the free end of the cable to the lever, and a hook mounted on the lower part of the gate

and adapted to connect with the lever and hold the same in an intermediate position. 10

In testimony whereof I affix my signature in presence of two witnesses.
